UNITED STATES PATENT OFFICE.

ROBERT FELSCHER, OF BRENHAM, TEXAS.

DESIGN FOR A PACKING-JAR.

SPECIFICATION forming part of Design No. 28,613, dated May 10, 1898.

Application filed February 18, 1898. Serial No. 670,864. Term of patent 14 years.

To all whom it may concern:

Be it known that I, ROBERT FELSCHER, a citizen of the United States, residing at Brenham, in the county of Washington and State of Texas, have invented and produced a new and original Design for a Packing-Jar for Cigars; and I do hereby declare the following to be a full, clear, and exact description of the same, reference being had to the accompanying drawings, forming a part thereof.

My invention relates to a design for a packing-jar for cigars and is illustrated in the accompanying drawings, in which—

Figure 1 is a perspective view of a jar embodying my design. Fig. 2 is a vertical sectional view of same.

The leading or material features of the design appear in the following description.

A represents a cylindrical stone jar having

an ornamental annular rim-flange *b* and an ornamental rectangular molding *c*, surrounding a smooth-surfaced field or panel *d*. On the jar is a cover or lid *D*, provided with an annular pendent flange *e*, inclosing a concavity *f* and an ornamental rim *g*. Projecting from the top of the cover is a knob *h*.

Having thus described my invention, what I claim as new, and desire to secure by Letters Patent, is—

The design for a packing-jar for cigars, substantially as herein shown and described.

In testimony whereof I affix my signature in presence of two witnesses.

ROBERT FELSCHER.

Witnesses:
